HAY PRESS.

APPLICATION FILED MAR. 26, 1906.

2 SHEETS-SHEET 2.

UNITED STATES PATENT OFFICE.

ELZEAR DORÉ, OF LAPRAIRIE, QUEBEC, CANADA.

HAY-PRESS.

No. 838,012.

Specification of Letters Patent.

Patented Dec. 11, 1906.

Application filed March 26, 1906. Serial No. 308,171.

To all whom it may concern:

Be it known that I, ELZEAR DORÉ, a subject of the King of England, residing at Laprairie, in the Province of Quebec, in the Dominion of Canada, have invented certain new and useful Improvements in Hay-Presses, of which the following is a full, clear, and exact description, such as will enable others skilled in the art to which it appertains to make and 10 construct the same.

This invention relates to new and useful improvements in hay-presses, the object of which is to render more certain the operation of the press, to expedite pressing the hay, and 15 to produce a simple, convenient, and economical machine for the required purpose, which may be produced for a minimum sum, which may be readily set up and connected for use in the field or other location for use, and 20 which may be operated with a minimum power, all as hereinafter more fully described, and specifically pointed out in the claims.

Referring to the accompanying drawings, in which similar characters of reference denote 25 like parts in all the views, Figure 1 is a side elevation of the feed end of the machine with the discharge-end portion broken away, as there are no novel features in that portion of the machine. Fig. 2 is a longitudinal vertical 30 sectional view taken approximately centrally through that part of the machine shown in Fig. 1 with the operative parts of the machine shown in full and in dotted positions. Fig. 3 is an end elevational view looking from 35 the left-hand side of Fig. 1. Fig. 4 is a transverse sectional view taken on line 4-4 of Fig. 1, as indicated by the arrow. Fig. 5 is a plan view of driving means adapted to be used in operating the machine. Fig. 6 is a partial 40 side elevational view and a partial sectional view of said driving means. Fig. 7 is a detached plan view of the bifurcated head 6.

Referring first to the press, 1 is the main frame, containing the usual compression-chamber, with flat springs 2 placed to extend 45 into said chamber, for well understood purposes, through slots cut in the wall of said compression-chamber.

3 is the plunger, which is provided on its 50 outer face with the casting 4, in which is pivotally mounted the end of a plunger-rod 5, which rod is seated at its opposite end in the open end of a head 6, as shown in Figs. 1 and 2, the said head being bifurcated and carry-

ing near the free end of the bifurcated portion a roller 7.

To the frame 1 are secured plates 8, through perforations in which are passed the shaft 9, on which is mounted the rockable lever 10, which, as will be noted, is provided with a slot 11, extending longitudinally thereof and in which rides the roller 7. Connected at one end with the lever 10 and at the opposite end with the head 6 is a link 12, which is free to turn on its pivotal supports and travel with the said lever, as shown in the various positions illustrated in Fig. 2; but owing to the fact that this link is formed of metal or other rigid material the link serves as a support for the head and roller and holds the roller in proper position in said slot. Connected with the lower end of the lever is a rod 13, the opposite end of this rod being held in the bifurcated portion 14 of the arm 15. This arm 15 is mounted on the vertical spindle 16 and extends, as shown in Figs. 5 and 6, into the path of the rollers 17, which depend from the rotatable member 18, mounted on the vertical spindle 19, while the conventional sweep 20^a is connected with this member 18 to cause rotation thereof, preferably by animal-power, through said sweep.

As the arm 15 is free to rotate on its spindle, it is evident that rotation of the member 18 will bring the rollers 17 into contact therewith and carry said arm to the position shown in dotted lines in Fig. 5, thus drawing on the rod 13, rocking the lever 10, and causing the upper end thereof to bear on the outer end of the plunger-rod and forcing the plunger into the compression-chamber, as shown in dotted lines in Fig. 2.

When the plunger has reached its limit of inward movement, the roller 17 is about to pass beyond the range of the arm 15, and when said roller passes said arm the pressure of the hay in the compression-chamber causes immediate retraction of said plunger, thereby causing the arm 15 to again assume its normal position, as shown in full lines in Fig. 5, where it is properly positioned to be impinged by the opposite roller 17 when it is advanced far enough in the rotation of the member 18, at which time the arm 15 is again advanced and the plunger is again forced inwardly, so that with each full rotation of the sweep the plunger is given two full strokes.

Depending from brackets 20 and pivotally

supported thereby are hangers 21, which are recessed, as shown, for reception of the plate 22, which extends to the frame 23, in which are mounted the spindles 16-19, before referred to. Opposite the recesses in said hangers are hollow lugs 24, in which are seated rods 25, the opposite ends of said rods being seated in hollow castings 26, which are bolted in position under the compression-chamber, whereby said rods 25 serve as braces for the hangers and through them to the plate 22. As the hangers are supported by means of bolts 27 passing through the plates 20, it is evident that said hangers may be removed when desired.

Mounted upon the frame of the compression-chamber and extending to a plane above the same is a standard 30, which is rigidly held in position by means of suitable securing means, and in proximity to said standard are bearings in which is rockably mounted a relatively Y-shaped yoke, the bifurcated portion of which depends with one arm at each side of the machine. Pivoted supported in the upper portion 31 of this yoke is a hay-packing member adapted to assist the feed to the compression-chamber, and for convenience of description this member is called a "fork" 32, the upwardly-extending portion of which is pivoted as described and extends beyond the pivotal portion upwardly, where a link 33 is connected, said link extending to and being pivotally mounted in the standard 30.

The arms 34 of the yoke pass downwardly at each side of the machine and are connected, by means of the rods 35, with the arm 36, which is fast to the spindle 16. As the sweep 20^a carries the member 18 with it, it also carries with it the segmental gears 37 and 38, and when one of these gear-sections comes into mesh with the gear 39 the arm 36 will be carried in the direction indicated by the arrow 40, thereby drawing on the rods or cables 35, rocking the yoke 31-34, and depressing the fork, which will pass into the compression-chamber of the machine. This last action takes place only after the plunger has been retracted, with a short interval of time to permit putting more hay into the compression-chamber and while the plunger is at its outermost position.

The plunger is provided at each side with rollers projecting laterally therefrom, as indicated at 41 in Fig. 4, said rollers being carried on short stub-shafts which project through slots 42 in the side walls of the machine, and when the plunger is forced into the compression-chamber these rollers impinge the legs 34 of the fork-carrying yoke, thereby quickly lifting said fork from the compression-chamber in advance of the arrival of the plunger.

In operation the draft-animals are connected with the sweep 20^a, which is caused to travel in the direction indicated by the ar-

row, and the member 18 is rotated, thereby causing the segmental gears 37 and 38 to alternately mesh with the gear 39 and causing the rollers 17 to alternately impinge the free end of the arm 15, thus alternately acting on the plunger-driving means and the fork-actuating means, with a slight intermission to permit filling the compression-chamber while the plunger is at the outer end of its stroke, and causing the plunger to be actuated twice for each full rotation of the sweep.

As it sometimes happens that the roller carried in the slot of the operating-lever is violently projected toward the upper end of the slot in said lever, there are provided abutment-blocks 45, which project into said slot, as shown in Figs. 1 and 2, which blocks are carried at the inner ends of the bolts 46, and on said bolts are the springs 47, which bear on said blocks to normally force the said blocks into said slot, while nuts at the inner ends of the bolts are provided to retract the blocks when desired, said nuts bearing on the outer sides of the lever for this purpose.

It is evident that the plunger may be retracted by means of the segments 37 38 being brought into mesh with the gear 39, if desired, thus carrying the arm 36 in the direction of the arrow 40 and carrying the arm 16 back to its normal position when the segments and said gear are enmesh.

While I have shown in the accompanying drawings the preferred form of my invention, it will be understood that I do not limit myself to the precise form shown, for many of the details may be arranged in different form or position without affecting the operativeness or utility of my invention, and I therefore reserve the right to make all such modifications as are included in the scope of the following claims or of mechanical equivalents to the structures set forth.

Having described the invention, what I claim is—

1. In a hay-press, the combination comprising a frame, a compression-chamber, a plunger, a plunger-rod connected therewith, a head in which said rod is seated, a roller carried by said head, a longitudinally-slotted rockable lever in the slot of which said roller may travel, a link pivotally connected with said head and with said lever, and means for rocking said lever.

2. In a hay-press, the combination comprising a frame, a compression-chamber, a plunger, a plunger-rod connected therewith, a bifurcated head in which said rod is seated, a roller carried in the bifurcation of said head, a longitudinally-slotted lever, rockable on a fixed pivot, in the slot of which lever said roller is adapted to travel, a link pivotally connecting said lever and said head, and means for rocking said lever.

3. In a hay-press, the combination com-

prising a frame, a compression-chamber, a plunger, a plunger-rod pivotally connected with said plunger, a socketed head, a roller carried by said head, a longitudinally-slotted rockable lever, in the slot of which said roller is adapted to travel, a link pivotally connected with said head and with said lever, rotatable actuating means, and means for causing said lever to rock a plurality of times 5 at each cycle of said driving means.

4. In a hay-press, the combination comprising a frame, including a compression-chamber; a plunger, a plunger-rod pivotally connected with said plunger, a bifurcated 15 and socketed head in the socket of which one end of said plunger-rod is seated, a roller supported in the bifurcated portion of said head, means for supporting said head, a rockable lever pivotally mounted on said frame, said 20 lever carrying said head-supporting means, and means for rocking said lever.

5. In a hay-press, the combination comprising a frame, including a compression-chamber; a plunger, a plunger-rod connected 25 with said plunger at one end, a socketed head in which the opposite end of said plunger-rod is seated, a roller rotatably mounted in said head, a longitudinally-slotted lever rockably mounted on said frame, supporting-links 30 pivotally connecting said lever and said head, means for rocking said lever, a feeding-fork rockably supported above said compression-chamber, said fork being provided with a bifurcated lower portion, and means 35 for rocking said fork to lift the same at each inward stroke of said plunger.

6. In a hay-press, the combination comprising a frame, including a compression-chamber; a plunger, a plunger-rod pivotally 40 connected with said plunger, a socketed head in which one end of said rod is seated, a roller carried by said head, a rockable lever adapted to bear on said roller, a link pivotally connected with said head and with said lever, a 45 fork-carrying yoke supported in a plane above said compression-chamber, said yoke having depending extensions at each side of the machine, a fork carried thereon, a link connecting said fork with said yoke, and 50 means for alternately carrying said fork and said plunger into said compression-chamber.

7. In a hay-press, the combination comprising a frame, including a compression-chamber; a reciprocatory plunger, a rockable lever mounted on said frame in proximity to said compression-chamber, a plunger-rod, a roller carried at the end of said plunger-rod away from said compression-chamber, means connected with said lever for supporting said roller in operative position with relation to said lever, a standard projecting to a plane above said compression-chamber, a rockable fork-carrying member mounted in a plane above said chamber, a link connected 65 with said standard, a fork pivotally connect-

ed with said link, and means for alternately rocking said lever to cause it to impinge said roller and to rock said fork-carrying member, whereby the plunger and the fork are alternately projected into said compression-chamber. 70

8. In a hay-press, a supporting-frame, a compression-chamber, a reciprocatory plunger, a rockable lever, a plunger-rod connected with said plunger, a roller carried at 75 the outer end of said rod, said lever being adapted to bear on said roller, means for actuating said lever, a rockable yoke journaled in a plane above said compression-chamber and extending to a plane therebelow, a fork 80 carried by said yoke, a rigid standard, a link connecting said standard with said fork, and a single-actuating means adapted to alternately force the said fork and the said plunger into the compression-chamber. 85

9. In a hay-press, the combination comprising a frame, a compression-chamber, a plunger and means for actuating the same, plates on said frame, recessed and pivoted hangers supported by said plates, hollow lugs 90 on said hangers, sockets on said frame and brace-rods seated in said frame-sockets and in the lugs on said hangers.

10. In a hay-press, the combination comprising a frame, a compression-chamber, a reciprocatory plunger, a plunger-rod pivotally connected with said plunger, an actuating-lever, a roller carried by said plunger-rod against which said lever is adapted to bear, means carried by said lever adapted to support said roller in operative position, a rockable fork-carrying yoke mounted in a plane above said compression-chamber, integral depending extensions on said yoke, laterally-extending rollers, carried by said plunger, 105 adapted to impinge said depending extensions, a rotatable sweep-carrying member, segmental gears carried with said rotatable member, a gear adapted to mesh with said segments at each rotation of said sweep-carrying member, a spindle on which said gear is mounted, an arm mounted on said spindle against which rollers on said rotatable member may impinge, a rod connecting said arm with said lever, a second arm mounted on 110 said spindle which latter arm is adapted to rotate with said gear, and means connecting said second arm with the extensions of said yoke. 115

11. In a hay-press, the combination comprising a frame, a compression-chamber, a plunger, a plunger-rod connected therewith, a head in which said rod is seated, a roller carried by said head, a longitudinally-slotted, rockable, lever in the slot of which there are 120 provided abutment-blocks, said roller being adapted to travel in said slot, a link pivotally connected with said head and with said lever, and means for rocking said lever. 125

12. In a hay-press, the combination com- 130

prising a frame, a compression-chamber, a reciprocating plunger, a plunger-rod pivotally connected therewith, a roller mounted at the opposite end of said lever, a slotted lever mounted on said frame, in the slot of which said roller is adapted to travel, abutment-blocks near the upper end of said slot, means for projecting said blocks into said

slot, means for retracting said blocks, and means for rocking said lever.

In testimony whereof I have hereunto set my hand in the presence of two witnesses.

ELZEAR DORÉ.
